WIRE TERMINAL

Joseph F. Merkel, Rochester, N. Y., assignor to
General Railway Signal Company, Rochester,
N. Y.

Application August 12, 1946, Serial No. 689,879

3 Claims. (Cl. 173—269)

1

This invention relates to wire terminals, and it more particularly pertains to terminals of the eyelet type in which the end of a wire to be attached to the terminal is formed around the opening in the eyelet.

In a wire terminal of a character conventionally employed, the eyelet is formed of yieldable material; the end of a wire is formed around the opening in the eyelet; and, by compressing the eyelet with a suitable tool, ears are formed downwardly over the wire to secure it within the eyelet. When a wire terminal of this character after being soldered is further compressed by tightening a nut on to it on a terminal post, the solder bond between the wire and the eyelet is often broken resulting in a poor electrical connection, and the soft strands of the wire are often broken due to such further compression of the eyelet.

An object of the present invention is to provide a wire terminal that is substantially non-compressible upon tightening a nut on the wire terminal by the use of a suitable non-yieldable tubular spacer as an insert in an eyelet, such spacer serving as an inner support for the attachment of a wire and being of sufficient height above the eyelet when a wire is applied to the terminal to absorb all of the compression of a nut tightened on to the terminal thus protecting the solder bond between the terminal and wire and the strands of the wire against damage.

Other objects, purposes, and characteristic features of the present invention will be in part obvious from the accompanying drawings and in part pointed out as the description of the invention progresses.

In describing the invention in detail, reference is made to the accompanying drawing in which corresponding parts are designated throughout the several views by like reference characters, and in which:

Fig. 1 is a plan view of a wire attached to a wire terminal;

Fig. 2 is an elevational view of a wire attached to a wire terminal with a portion shown in cross section as taken along the section line 2—2 of Fig. 1;

Fig. 3 is a plan view of a spacer used in the wire terminal assembly shown in Fig. 1;

Fig. 4 is an elevational view of the spacer with a portion shown in cross section as taken along the section line 4—4 of Fig. 3;

Fig. 5 is a plan view of an eyelet used in the wire terminal assembly shown in Fig. 1; and

Fig. 6 is an elevational view of the eyelet shown

2

partly in cross section as taken along the line 6—6 of Fig. 5.

With reference to Figs. 5 and 6, the eyelet 10 used in this embodiment of the present invention is formed circular in shape of yieldable material having low electrical resistance such, for example, as copper, with ears 11 spaced about the periphery and formed upwardly from the base 10a of the eyelet. A sleeve 12 for supporting the wire at the point of its connection to the wire terminal extends from the right of the terminal as shown in Figs. 5 and 6, and comprises the ears 13 which are formed upwardly for use in clamping down on the insulation of a wire when it is attached to the terminal as shown in Fig. 1. Inasmuch as the sleeve 12 clamps on to the insulation of the wire it is offset slightly downwardly as illustrated in Fig. 6 from the base 10a of the eyelet to an extent substantially comparable to the thickness 20 of the insulation of the wire.

The spacer 14 of substantially non-yieldable material is substantially tubular in shape, having a base portion of an outside diameter to be receivable within the opening 15 of the eyelet 10. The spacer 14 is receivable within the opening 15 of the eyelet 10 only to the extent limited by the shoulder 16 which allows the spacer 14 to be receivable within the opening 15 of the eyelet 10 only to an extent not greater than the thickness 30 of the base 10a of the eyelet. The opening 9 in the spacer is of a size determined by the diameter of the binding post to which the wire connection is to be applied.

A groove 17 is formed in the periphery of the spacer to conform to the shape of a wire to be connected to the terminal, and the flange 18 at the lower edge of the groove 17 is provided to facilitate in forming the wire strands 20 within the groove 17. The flange 18 is of a diameter 40 only slightly less than the diameter of the area within the upwardly formed ears 11 of the eyelet 10.

In the connection of the wire 19 to the terminal the spacer 14 is inserted within the opening 15 in the eyelet 10, and the insulation of the wire is removed to an extent to allow the wrapping of the strands 20 of the wire around the spacer 14 in the groove 17, preferably as shown in Fig. 1, with the strands 20 of the wire divided and substantially half of the strands extending around the spacer 14 each way to be joined at the point 21 at the left-hand end of the terminal and twisted together at that point.

The strands 20 of the wire 19 are clamped within the groove 17 of the spacer 14 by bending the

ears 11 of the eyelet inwardly, preferably with a suitable tool provided for this purpose. After the ears are formed as shown in Figs. 1 and 2 to clamp the strands 20 within the groove 14 the solder 22 is properly applied to the left-hand end of the terminal to secure the twisted strands of the wire at the point 21 shown in Fig. 1, and when the solder is thus applied it flows to provide a bond between the eyelet 10 and the strands 20 of the wire and the spacer 14.

To complete the assembly of a wire 19 to the terminal T, the ears 13 of the eyelet 10 are bent inwardly around the insulation of the wire 19 as shown in Figs. 1 and 2 to securely support the wire at the point of its attachment to the wire terminal T, and thus limit the flexing of the wire 19 at the point of its connection to the wire terminal T.

With reference to Fig. 2 it will be noted that when the wire 19 is completely assembled to the terminal T, and the ears 13 are bent inwardly, the spacer 14 extends slightly above the ears 11 of the eyelet and therefore the surface 23 of the spacer 14 absorbs the full pressure applied to the terminal T when a nut is tightened on to the terminal in its assembly to a terminal post. Inasmuch as the spacer 14 is rigidly constructed to withstand considerable pressure, a nut may be tightened upon the terminal as tightly as desired without in any manner disturbing the bond of the soldered connection or to in any manner damage the strands 20 of wire 19.

Having thus described a specific wire terminal as one embodiment of the present invention, it is desired to be understood that this form is selected to facilitate in the disclosure of the invention rather than to limit the number of forms this invention may assume, and it is to be understood that various adaptations, alterations, and modifications may be applied to the specific form shown to meet the requirements of practice, without in any manner departing from the spirit or scope of the present invention except as limited by the appending claims.

What I claim is:

1. A wire terminal comprising an eyelet having several ears formed upwardly about its periphery and having a center opening, and a tubular spacer of substantially non-yieldable material receivable within said upwardly formed ears and concentric with said opening in said eyelet, said

spacer having a flange at its base bearing against the inner base surface of said eyelet, said flange being of a diameter only slightly less than the diameter of the opening formed within said ears, and said spacer extending upwardly from said inner base surface of said eyelet to an extent to space the ears of said eyelet from a nut securing said terminal to a terminal post when said ears are formed inwardly to secure a wire between said ears and the periphery of said spacer.

2. In combination, an eyelet having several upwardly extending ears about its periphery and having a center opening of a substantial diameter, a tubular spacer of substantially non-yieldable material having a shoulder of reduced diameter extending downwardly from its base, said shoulder being of a diameter to fit within said opening and of a depth substantially comparable to the thickness of the base of said eyelet, said spacer having a groove formed about its periphery for receiving a wire, and said spacer extending upwardly from the base of said eyelet sufficiently to space the upper side of said eyelet from a nut securing said terminal to a terminal post when said ears are formed inwardly so as to clamp a wire within said groove.

3. The combination with an eyelet having ears formed upwardly about its periphery and having a center opening, of a tubular spacer of relatively non-yieldable material having a groove extending about its periphery for receiving a wire, said spacer being receivable within said ears of said eyelet concentric with said opening whereby said ears when formed inwardly secure a wire wrapped around said spacer, and said spacer extending upwardly from the inner surface of said eyelet to an extent to space the ears of said eyelet from a nut securing said terminal to a terminal post when said ears are formed inwardly to secure a wire within said groove.
